US00D377904S

United States Patent [19]

Hestehave et al.

[11] Patent Number: Des. 377,904

[45] Date of Patent: **Feb. 11, 1997

[54] CYLINDRICAL CONTAINER

[75] Inventors: **Borge Hestehave**, Alta Loma; **Kield Hestehave**, Upland, both of Calif.

[73] Assignee: **Bomatic, Inc.**, Ontario, Calif.

[**] Term: 14 Years

[21] Appl. No.: 30,120

[22] Filed: Nov. 2, 1994

[52] U.S. Cl. D9/552

[58] Field of Search D9/552, 565, 538, D9/537-541, 556, 500, 503; 215/382, 383, 400

[57] CLAIM

The ornamental design for a cylindrical container, as shown and described.

DESCRIPTION

FIG. 1 is a vertical elevational view showing a first embodiment of our design, except for the neck, the design appearing the same when viewed from each side thereof;
FIG. 2 is a top view of the design shown in FIG. 1;

FIG. 3 is a bottom view of the FIG. 1 embodiment;
FIG. 4 is a fragmentary rear elevational view of the neck of FIG. 1;

FIG. 5 is a fragmentary right side elevational view of the neck of FIG. 1;

FIG. 6 is a fragmentary left side elevational view of the neck of FIG. 1;

FIG. 7 is a vertical elevational showing a second embodiment of our design, except for the neck, the design appearing the same when viewed from each side thereof;

FIG. 8 is a top view of the design shown in FIG. 7;

FIG. 9 is a bottom view of the design shown in FIG. 7;
FIG. 10 is a fragmentary rear elevational view of the neck of the FIG. 7;

FIG. 11 is a fragmentary right side elevational view of the neck of the FIG. 7;

FIG. 12 is a fragmentary left side elevational view of the neck of the FIG. 7;

FIG. 13 is a vertical elevational showing a third embodiment of our design, except for the neck, the design appearing the same when viewed from each side thereof;

FIG. 14 is a top view of the design shown in FIG. 13;

FIG. 15 is a bottom view of the design shown in FIG. 13;
FIG. 16 is a fragmentary rear elevational view of the neck of the FIG. 13;

FIG. 17 is a fragmentary right side elevational view of the neck of the FIG. 13;

FIG. 18 is a fragmentary left side elevational view of the neck of the FIG. 13;

FIG. 19 is a vertical elevational showing a fourth embodiment of our design, except for the neck, the design appearing the same when viewed from each side thereof;

FIG. 20 is a top view of the design shown in FIG. 19;

FIG. 21 is a bottom plan view of the design shown in FIG. 19;

FIG. 22 is a fragmentary rear elevational view of the neck of the FIG. 19;

FIG. 23 is a fragmentary right side elevational view of the neck of the FIG. 19;

FIG. 24 is a fragmentary left side elevational view of the neck of the FIG. 19;

FIG. 25 is a vertical elevational showing a fifth embodiment of our design, except for the neck, the design appearing the same when viewed from each side thereof;

FIG. 26 is a top view of the design shown in FIG. 25;

FIG. 27 is a bottom view of the design shown in FIG. 25;

FIG. 28 is a fragmentary rear elevational view of the neck of the FIG. 25;

FIG. 29 is a fragmentary right side elevational view of the neck of the FIG. 25;

FIG. 30 is a fragmentary left side elevational view of the neck of the FIG. 25;

FIG. 31 is a vertical elevational showing a sixth embodiment of our design, except for the neck, the design appearing the same when viewed from each side thereof;

FIG. 32 is a top view of the design shown in FIG. 31;

FIG. 33 is a bottom view of the design shown in FIG. 31;

FIG. 34 is a fragmentary rear elevational view of the neck of the FIG. 31;

FIG. 35 is a fragmentary right side elevational view of the neck of the FIG. 31; and,

FIG. 36 is a fragmentary left side elevational view of the neck of the FIG. 31.
